10

ABSTRACT OF THE DISCLOSURE

The selective oxidation of the alpha, beta-carbon atoms of lower alkyl radicals having functionally unsaturated groups, in the presence of sulfides of antimony, arsenic or bismuth to produce the alpha, beta unsaturated derivatives.

15

This application is a continuation-in-part of our co-pending application Serial No. 550,931, filed May 18, 1966, as a continuation-in-part of Serial No. 152,630, filed November 15, 1961, now abandoned, which was co-pending with and a continuation-in-part of our application Serial No. 10,107, filed February 23, 1960, now abandoned.

20

This invention relates to selective oxidation of unsaturated aliphatic hydrocarbon derivatives. More particularly the invention relates to selective oxidation of an alkyl derivative having a functional group in which functional unsaturation occurs, to produce a corresponding olefinic derivative.

25 and

The principal object of the invention is to provide a method for selective oxidation of a compound consisting of a lower alkyl radical attached to a functional group in which functional unsaturation occurs, and by such oxidation to produce the corresponding alpha-beta unsaturated compound. Another object of the invention is to provide a method for reacting an aliphatic derivative with a sulfide of antimony, arsenic or bismuth to produce such alpha-beta unsaturated olefinic derivatives.

30

The invention provides a method for selective oxidation at the alpha and beta carbon atoms of the alkyl radical in compounds consisting of a lower alkyl radical attached to a functional group in which functional unsaturation occurs between the first carbon atom and an adjacent atom.

35

By "functional unsaturation" as the term is used in this specification we mean an unsaturated linkage, either a double bond or a triple bond, between two atoms of a functional group (between the first carbon atom and an adjacent atom of the functional group in the instance of the invention). To illustrate, in the functional group of ketones

40

functional unsaturation as we use the term occurs at the double bond between C and O.

55

Functional unsaturation occurs between the first car-

2

bon atom and an adjacent atom in the following functional groups for instance:

Thus, alkyl derivatives such as

are oxidized to the corresponding alpha, beta-unsaturated derivatives

45

50

We have found that selective oxidation of the alpha, beta-carbon atoms of the alkyl radical is accomplished by action of an oxidizing agent consisting of one of, or a mixture of, the sulfides of arsenic, antimony, and bismuth. When contacted with the "functionally unsaturated" organic compound at elevated temperatures, the metal sulfide is reduced and yields sulfur which combines with hydrogen from the alpha and beta carbon atoms of the oxidized compound. An alpha, beta-unsaturated compound is produced.

Therefore, according to the invention, vapor of a compound having the formula:

saturated compounds useful in the process of our invention the substituent X is typically of the formula:

(a)

(b)

or

(c)

in which R⁴, when taken singly, is typically hydrogen, alkyl, hydroxy, or alkoxy. The substituents R¹, R² and R³, when taken singly, are hydrogen or alkyl. The substituents R¹ and R³, when taken collectively, represent joined alkylene groups completing a saturated carbocyclic ring having 5 to 6, preferably 6, carbon atoms in the ring; and the substituents R¹ and R⁴, when taken collectively, represent joined alkylene groups completing a saturated carbocyclic ring having 5 to 6, preferably 6, carbon atoms in the ring.

The substituents R¹, R², R³ and R⁴, when alkyl, are typically alkyl of 1 to about 8 carbon atoms and are preferably lower alkyl, e.g., alkyl of 1 to about 4 carbon atoms. When R⁴ is alkoxy, it typically contains an alkyl moiety of 1 to about 8 carbon atoms. The alkyl moiety of the alkoxy group represented by R⁴ is preferably lower alkyl, e.g., alkyl of 1 to about 4 carbon atoms.

Typical of the alkyl groups represented by R¹, R², R³, and R⁴ are methyl, ethyl, propyl, isopropyl, butyl, isobutyl, sec-butyl, tert-butyl, etc. The substituent R⁴, when alkoxy, is typically methoxy, ethoxy, propoxy, isopropoxy, butoxy, isobutoxy, sec-butoxy, tert-butoxy, etc.

When R¹ and R³ collectively represent joined alkylene groups completing a carbocyclic ring, the carbocyclic rings so represented are typically cyclopentyl or cyclohexyl. When R¹ and R⁴ collectively represent joined alkylene groups completing a carbocyclic ring, the carbocyclic rings so represented are typically cyclopentyl or cyclohexyl.

The alpha,beta-unsaturated compounds formed in the process of our invention can be represented by the formula:

in which R¹, R², R³ and X are as defined hereinbefore, when the functionally unsaturated compound employed has only one alpha-beta position capable of being oxidatively dehydrogenated.

When the functionally unsaturated compound has two or more alpha-beta positions capable of being oxidatively dehydrogenated, dehydrogenation can occur at both positions. Thus, diethyl ketone can react with an antimony sulfide to form divinyl ketone. In a particularly interesting embodiment of this aspect of our invention, cyclohexanone reacts with an inorganic sulfide apparently to form 2,5-cyclohexadiene-1-one or 2,4-cyclohexadiene - 1 - one which immediately rearranges to phenol.

Typical of the functionally unsaturated compounds which are useful in the process of our invention are compounds such as propionaldehyde, methyl ethyl ketone, propionic acid, methyl propionate, cyclohexanone, ethylbenzene, 1-butene, cyclohexanecarboxaldehyde, methyl cyclohexanecarboxylate, cyclohexanecarboxylic acid, cyclohexyl benzene, etc.

The process of our invention involves a reaction between the functionally unsaturated compound and the selected metal sulfide. For example, isobutyraldehyde reacts with an arsenic sulfide to form methacrolein, hydrogen sulfide, and a reduced form of the arsenic sulfide, or elemental arsenic.

The mechanics of the process consist simply of contacting the organic compound to be oxidized with a metal sulfide in a reaction zone at a temperature between 100° C. and 600° C., preferably between 150° C. and 500° C.

This is conveniently done by passing a stream of vapor of the organic compound through a reaction vessel packed with particles of the selected metal sulfide. Fine particles of the metal sulfide are preferred because more surface area per unit of volume will be available for contact with the organic vapor. In some cases it may be advantageous to dilute the vapor stream with nitrogen or other inert gas to control the temperature in the reaction zone, to reduce the rate of side-reactions, and to facilitate removal of reaction products from the reaction zone. The optimum

ratio of the volume of diluent gas per volume of organic vapor will depend upon the reactants being used and the reaction temperature and contact time but will usually be within the range from 0 to 2.0 volumes inert gas per volume of organic vapor. The process is operable within wide ranges of temperature, pressure and contact time. However, because of sensitivity of organic compounds to changes in temperature under oxidative conditions, consideration must be given to the relation of operating variables. For instance, the permissible range of contact

time will be different at various temperatures within the preferred temperature range. With increase in temperature, the contact time must be decreased commensurately to avoid excessive consumption of organic feed stock in side-reactions. The optimum contact time will be a function of the organic and metal sulfide reactants chosen and of the reaction temperature but will usually fall within the range from about 0.1 to about 75 seconds. The term "contact time" as used in this specification is defined as the ratio of bulk contact mass volume (for instance in cubic feet) to reactant vapor feed rate (for instance in cubic feed per second). This is to be distinguished from exposure time for the metal sulfide which is the total time a sample of solid metal sulfide is exposed to reactants in the reaction zone.

To the extent found necessary, temperature in the reaction zone may be regulated by controlling feed temperature and, when a diluent is used, by controlling the ratio of diluent to reactant in the feed stream. The reaction proceeds at a temperature above about 100° C. and reactions conducted at temperatures between about 325° C. and 475° C. give good product yields. Good yields are obtained at atmospheric pressure which is preferred for economic reasons, but the pressure in the reaction zone may be varied.

The sulfide or mixture of sulfides selected for a particular reaction and the valence state of the sulfide or mixture of sulfides must be considered as factors having marked influence on the choice of operating conditions. A sulfide in which the metallic element is present in a higher valence state, a valence of 5 for example, is more vigorous in oxidative action than one in a lower valence state. Less severe operating conditions such as lower reaction temperature and decreased contact time can therefore be employed when a sulfide of the higher valence state is used. Also, oxidation activity of the metal sulfides in a given valence state tends to increase as sulfides of metal in descending order in the periodic series are selected. For example, arsenic pentasulfide requires higher operating temperatures and/or more prolonged contact times for a comparable production unsaturates than does antimony pentasulfide. The flexibility in operating conditions made possible by varying degrees of oxidation activity of the sulfides or mixtures thereof can be of considerable importance in selection of a suitable sulfide and suitable operating conditions, since the heat stability and reaction stability of the various organic compounds which may be oxidized will differ.

The following examples are given to illustrate the invention.

Example 1

A volume of 29 ml. of 4×20 mesh arsenic pentoxide was charged to a 1-inch Vycor reactor and converted to the sulfide form by treatment with gaseous hydrogen sulfide at a temperature of 325° C. When reaction is com-

plete, the temperature drops and no more water is produced. It is noted that an operable mixture of sulfides results. After flushing the reactor free of residual hydrogen sulfide with nitrogen, the sulfided mass was contacted with 3.6 g. of isobutyraldehyde during a period of 32 minutes. Gas chromatographic analysis of the liquid product collected in cooled receivers showed the presence of methacrolein. Analysis of the gaseous effluent showed the presence of hydrogen sulfide thereby demonstrating the occurrence of oxidative dehydrogenation analogous to that occurring while employing the oxide form of the contact mass.

Example 2

A volume of 50 ml. of 4×20 mesh antimony (IV) oxide was charged to a 1-inch Vycor reactor and converted to the sulfide form by treatment with hydrogen sulfide at a temperature of 460° C. After flushing the reactor free of residual hydrogen sulfide, the sulfided mass was contacted with 15.7 g. of isobutyraldehyde during a period of 44 minutes. Examination of the reactor effluent as before showed the presence of methacrolein and hydrogen sulfide.

Using the apparatus and procedural methods of Examples 1 and 2, a number of lower aliphatic derivatives may be reacted with sulfides of arsenic, antimony, and bismuth to produce the corresponding alpha-beta unsaturated derivative. Data and results of these reactions are tabulated in Table 1.

TABLE I

Example No.	Alkyl Derivatives	Sulfide Oxidizing Agent From—	Reaction Zone Temp.	Contact Time, sec.	Product	Approximate Expected Conversion, percent
3.....	n-Butyraldehyde.....	Sb ₂ O ₄	430	6-7	Crotonaldehyde.....	20

Alkyl derivatives having functional groups without functional unsaturation may be substituted in the process and although oxidation occurs there is a marked lack of specificity of reaction. A number of useful oxidation products are produced. Isobutyl alcohol may be oxidized to a mixture including substantial amounts of isobutyraldehyde, methacrolein, methallyl alcohol, as well as some other products. Similarly, arrays of oxidation products may be obtained from n-propyl alcohol and ethyl chloride.

The particular solid oxidant selected for use may be obtained in various ways such as by oxidation of the free metal or a mixture of free metals taken alone or in any desired proportions, by known chemical methods. Or, intermediate or lower sulfides or their mixtures may be formed by thermal decomposition and/or chemical reduction of higher sulfides or suitable mixtures thereof. Methods for affecting these various transpositions are a matter of record and may be found by reference to the usual sources such as textbooks on inorganic chemistry. In the same manner, samples of oxidant that have lost dehydrogenating activity due to conversion to a lower sulfide or other inactive species can be regenerated by suitable chemical treatment to form the starting oxidant.

The sulfides selected for use in the process of the invention may be used in the form of solid particles of the sulfide or may be suspended on a carrier such as silica gel, alumina or silica by conventional procedures. Small particles of the selected sulfide can conveniently be used in a conventional circulating-fluidized-bed reactor with the advantage that fresh sulfides may be continuously introduced into the reaction zone as spent solids are removed for regeneration.

In all of the above examples only one alpha-beta posi-

75

70

75

70

tion could be oxidized to form a double bond. With compounds in which oxidation to form a double bond can occur at two alpha-beta positions, both positions may be oxidized by the process of this invention. Some examples of such compounds are dialkylketones such as diethylketones, dialkylthioketones, dialkylvinyl compounds and dialkyl benzenes. These are oxidized by the process of the invention to the corresponding dialkenyl derivatives. The reaction product may contain some of both the singly and the doubly oxidized derivatives.

Example 12

During a period of about 15 minutes, 13.8 g. of diisobutyl ketone is passed over a sample of a sulfide obtained by treating 4×20 mesh arsenic pentoxide with hydrogen sulfide. The initial volume of the contact agent is about 50 ml. The temperature is adjusted to about 450° C. in the Vycor tube of Example 1. Phorone and isophorone are identified in the product. The formation of phorone further demonstrates the principle of extended dehydrogenation where more than one alpha-beta position is available for reaction. Isophorone would be expected from a Michael's reaction involving conjugate addition of an active methylene component to an alpha, beta-unsaturated compound.

In cyclohexanone an interesting double alpha-beta

oxidation occurs to form an unstable alpha-beta diene derivative that rearranges to phenol.

Example 13

A contact agent prepared as in Example 12 is contacted with 6.2 g. of gaseous cyclohexanone and 3000 ml. of nitrogen. From the product approximately 2 g. of phenol in addition to unreacted cyclohexanone is isolated.

Though the invention has been described with reference to certain preferred embodiments, it will be understood that variations and modifications can be made within the scope of the invention as defined in the following claims.

We claim:

1. The process which comprises reacting at least one compound from the group of sulfides of arsenic, antimony, or bismuth with a functionally unsaturated compound of the formula:

in which X is a functionally unsaturated group selected from those of the formula:

or

(c)

each of R¹, R², and R³, when taken singly, is selected from:

- (a) hydrogen or
  - (b) alkyl;
- R₄, when taken singly, is selected from:
- (a) hydrogen
  - (b) alkyl
  - (c) hydroxy or
  - (d) alkoxy;

R¹ and R³, when taken collectively, represent joined alkylene groups completing a saturated carbocyclic ring having 4 to 6 carbon atoms in the ring; and R¹ and R⁴, when taken collectively, represent joined alkylene groups completing a saturated carbocyclic ring having 4 to 6 carbon atoms in the ring.

2. The process of claim 1 in which the reaction is carried out by contacting the sulfide of arsenic, antimony, or bismuth with the functionally unsaturated compound for about 0.1 to about 75 seconds at a temperature above 100° C.

3. The process of claim 2 in which the functionally unsaturated compound is isobutyraldehyde and the products of the reaction include methacrolein and hydrogen sulfide.

4. The process of claim 2 in which the functionally unsaturated compound is n-butyraldehyde and the products of the reaction include crotonaldehyde and hydrogen sulfide.

5. The process of claim 2 in which the functionally unsaturated compound is isobutyric acid and the prod-

ucts of the reaction include methacrylic acid and hydrogen sulfide.

6. The process of claim 2 in which the functionally unsaturated compound is n-butyric acid and the products of the reaction include crotonic acid and hydrogen sulfide.

7. The process of claim 2 in which the functionally unsaturated compound is methyl isobutyrate and the products of the reaction include methyl methacrylate and hydrogen sulfide.

8. The process of claim 2 in which the functionally unsaturated compound is propionaldehyde and the products of the reaction include acrolein and hydrogen sulfide.

9. The process of claim 2 in which the functionally unsaturated compound is ethylbenzene and the products of the reaction include styrene and hydrogen sulfide.

10. The process of claim 2 in which the functionally unsaturated compound is cyclohexanone and the products of the reaction include phenol and hydrogen sulfide.

11. The process of claim 2 in which the functionally unsaturated compound is methyl ethyl ketone and the products of the reaction include methyl vinyl ketone and hydrogen sulfide.

12. The process of claim 2 in which the functionally unsaturated compound is butene-1 and the products of the reaction include butadiene and hydrogen sulfide.
